REMOTE CONTROL SYSTEM

Paul K. Eckhardt, O'Hara Township, Allegheny County, Pa., assignor to The Union Switch & Signal Company, Swissvale, Pa., a corporation of Pennsylvania

Application February 17, 1949, Serial No. 76,972

16 Claims. (Cl. 177—353)

1

My invention relates to remote control systems and more particularly to centralized traffic control systems for railroads, in which traffic governing devices located along a trackway are governed from a control office and the conditions of the devices and associated apparatus are indicated at such office.

In systems of the type described, the office is linked with the traffic governing devices along the trackway by means of a communication system which may be of any suitable type, such as, for example, the direct wire, carrier-selective, or code-type, one example of the latter being shown in Letters Patent of the United States No. 2,411,375, granted November 19, 1946, on an application filed by Arthur P. Jackel, for Remote control systems.

In a code system of the type mentioned, two steps in the indication code are used as channels to indicate a three-position traffic governing device. For example, a track switch is a three-position device having a normal, a reverse and an intermediate position and is indicated over two channels arranged in such manner that one channel indicates whether or not the switch is locked in its normal position, and the other channel indicates whether or not the switch is locked in its reverse position. Thus when the switch is locked in either its normal or its reverse position it provides one character for the code step which indicates that the switch is locked in the corresponding position, and provides a different character for the other code step. When the switch is unlocked by the switch machine, as when the switch points are in transit between extreme positions, the code intervals of the two switch indication steps both have the different character mentioned, to indicate the transit condition. The two steps are capable of indicating a fourth condition if both have the one character referred to, but the switch obviously is not adapted to afford a control which establishes this character for both steps, and the full capacity of the code ordinarily is not utilized.

It has been proposed heretofore to make use of this fourth code condition (in which both steps have the one code character) to indicate a two-position device, for example, as shown in the co-pending application for Letters Patent of the United States, Serial No. 665,018, filed April 26, 1946, by Joseph A. Quinlan; in Letters Patent of the United States No. 2,460,336, granted February 1, 1949, to Ira F. Cadman; and in Letters Patent of the United States No. 2,460,337, granted February 1, 1949, to Henry S. Young; all of which

have been assigned to the assignee of the present application.

One object of my invention is to provide novel and improved means in which the two indication channels of a centralized traffic control system required to indicate a three-position device at a station, are employed to indicate also a two-position device at that station.

Another object of my invention is to provide an improved system of the type shown in the aforementioned Quinlan application Serial No. 665,018, in which there is obtained an additional indication relating to a two-position device on two indication steps of a code which are normally arranged to provide three indications one for each position of a three-position device, which additional indication is provided by means which function to indicate changes in position of both of the devices, or of either of them without affecting the indication of the other.

A specific object of my invention is to simplify and improve the apparatus shown in the Quinlan application, Serial No. 665,018, for utilizing the indication steps which indicate the position of a remotely controlled power-operated track switch to indicate also a two-position device at the location of such track switch. Other features of my invention will be pointed out in detail in the accompanying specification.

I shall describe two forms of apparatus embodying my invention, and shall then point out the novel features thereof in claims.

In the accompanying drawings, Fig. 1 is a diagrammatic view illustrating one form of apparatus embodying my invention. Fig. 1a is a view showing a modified form of the apparatus shown in Fig. 1. In Fig. 1a, each of the circuit elements is identified by reference characters corresponding to those used in Fig. 1 and it will be understood that the designation of a relay of Fig. 1 placed above a relay contact of Fig. 1a indicates that such a contact is operated by the relay thus identified, as for example, the designation NWP placed above contact 3 of Fig. 1a indicates that contact 3 is operated by relay NWP illustrated in Fig. 1.

Referring to the drawing, a centralized traffic control system is represented as comprising apparatus at an office and at a station, and a communication system linking the office with the station.

The communication system, which as previously mentioned may be of any suitable type, is conventionally represented in the drawing as being a code system of the type illustrated in the

previously mentioned Jackel patent. For the purposes of explaining the present invention it is sufficient to state that the communication system provides a number of control channels (not represented in the drawing), and a number of indication channels some of which are represented in the drawing by dash lines, with the wires of each channel designated by reference characters which are the same as those used to designate corresponding wires in the Jackel patent. For example, the indication channels 49-139 and 51-141 represent individual code steps of an indication code, and the system functions in the manner explained in the Jackel patent so that if one terminal B of a suitable local source of current at the station is connected to wire 139 when an indication code is transmitted, the code will include a step of a particular character corresponding to the energization of channel 49-139, to cause terminal B of a source at the office to be applied to terminal 49. If terminal B is not connected to wire 139 when an indication code is transmitted, the code will include a step of a different character corresponding to the deenergization of channel 49-139, and in such case terminal B at the office is not applied to wire 49. Similarly, if terminal B at the station is connected to wire 141 when an indication code is transmitted, the code will include a step of a particular character corresponding to the energization of channel 51-141 to apply terminal B at the office to wire 51, but if terminal B at the station is disconnected from wire 141 when an indication code is transmitted, the code then includes a step of a different character corresponding to deenergization of channel 51-141.

The apparatus at the office, as indicated in the drawing, includes an office delivery relay D which corresponds to the office delivery relay D of the Jackel patent and which is picked up at the office at the end of a complete indication code received from the station, as is explained in detail in the Jackel patent, and a normal indication relay NWK and a reverse indication relay RWK selectively picked up according as energy is applied to terminal 49 or 51 at the office when the office delivery relay D is picked up. The pickup circuit of each indication relay includes a back contact of the other indication relay so that each relay NWK or RWK when picked up opens the pickup circuit of the other relay to insure that only one of the two indication relays can be picked up at any time. Each relay NWK or RWK when picked up is held energized over a stick circuit including its own front contact and a back contact of relay D, when the latter relay releases at the end of an indication code. Indication lights NWE and RWE are controlled respectively by relays NWK and RWK so as to be illuminated or dark according as the associated relay is picked up or released.

In addition to the apparatus above described, I provide in accordance with my invention an office intermediate relay OIR, another indication relay CHK, and two other indication lamps 1CCK and 2CCK. The intermediate relay OIR is arranged as will be explained in detail hereinafter to pick up whenever both indication relays NWK and RWK are released, or whenever with either of those two indication relays picked up, an indication code is received which includes a step of the character corresponding to the energization of the channel of the other indication relay. Relay OIR has a stick circuit which includes its own front contact and a front contact of the

delivery relay D. Relay CHK is arranged to pick up if with either of the two indication relays NWK or RWK picked up, an indication code is received which places energy on both indication channels so that the picked up indication relay is held up, the intermediate relay OIR becomes picked up, and when relay D picks up relay CHK is energized and picks up. Relay CHK when picked up at times is provided with a stick circuit which of course includes a front contact of the relay, and has a number of branches, one completed when relay D is released, and others completed with relay D picked up, as will be explained in detail hereinafter. Relay CHK controls indication lamps 1CCK and 2CCK so as to energize one or the other of such lamps according as the relay is released or picked up, respectively.

The apparatus at the station includes a plurality of elements, such as a signal (not shown), a three-position device, such as a track switch W provided for a stretch of track and having a normal, a reverse, and an intermediate position, a power switch operating mechanism SM operatively connected with the switch for operating it between its two extreme (normal and reverse) positions and controlling a contact I according to the position of the switch, switch repeating relays NWP and RWP selectively energized over contact I according as switch W is locked in its normal or reverse extreme position, a track relay TR connected in a track circuit including a track battery TB, provided for the track section T which includes the point of switch W, a starting relay ST and a field station disconnect relay RPP corresponding respectively to the similarly designated relays shown in the Jackel patent, a field intermediate relay FIR hereinafter referred to, and a two-position device (such as a relay CH) which is to be indicated at the office on the switch indication steps by use of my novel and improved arrangement of apparatus.

The switch operating mechanism SM is controlled by means of apparatus and equipment not illustrated in the attached drawing for the sake of simplicity but which may take the form shown and described for controlling the switch FW of the Jackel patent. For the purposes of the present description it is sufficient to state that the system organization is such that the operator at the office is enabled to control the switch mechanism SM to cause it to operate the switch W to and lock it in its normal or reverse position, it being understood of course that the switch can be unlocked by the switch mechanism for movement only when traffic conditions on the stretch are favorable for such operation.

The starting relay ST is controlled in the manner explained in detail in the Jackel patent, and is normally energized over a stick circuit which includes contact 2 of relay ST (closed in the energized position of the relay in which contact 2 operates to its left-hand position as viewed in the drawing) the winding of relay ST and contacts of each of the relays NWP, RWP, TR, FIR, and CH. Alternatively, as indicated in Fig. 1a, the stick circuit of relay ST may be arranged to include a contact of relay FIR only when relay CH is in its operated or right-hand position, as will be made clear presently. In either case the stick circuit of relay ST may also include contacts of other relays such as shown in the Jackel patent, and the arrangement is such that upon change in position of any of the relays having a contact in the stick circuit of relay ST, the stick circuit is opened

and relay ST operates its contacts to their right-hand position in which contact 14 closes to initiate the transmission of an indication code to the office in the manner explained in the Jackel patent. After the transmission of a portion (the station registering part) of that code has been completed, the station apparatus is arranged to pick up relay ST over a circuit in which terminal B is applied to wire 114 in the manner pointed out in the Jackel patent, whereupon relay ST operates its contact 2 to its normal or left-hand position to re-establish its stick circuit.

The field station disconnect relay RPP is controlled in a manner (not shown in the drawing to avoid unduly complicating it) corresponding to that illustrated and described for the correspondingly designated relay of the Jackel patent, and for the purposes of the present application it is deemed sufficient to state that relay RPP remains energized in the normal operation of the system, but can be deenergized at the will of the operator in the office through the medium of the communication system. Relay RPP when released renders the associated station equipment inactive so that indication codes cannot be transmitted.

The field intermediate relay FIR is picked up whenever relay RPP is released to close its back contact 15 to complete an obvious circuit for relay FIR, or whenever both relays NWP and RWP are released with relay RPP picked up, in which event relay FIR is energized over a circuit which may be traced from terminal B through back contact 16 of relay NWP, back contact 17 of relay RWP, front contact 15 of relay RPP and the winding of relay FIR to terminal C. Relay FIR is provided with a stick circuit completed when contact 14 of relay ST is closed in its operated or right-hand position (in which the transmission of an indication code is initiated) provided that relay RPP and either one or both of the switch repeating relays are picked up. The stick circuit may be traced from terminal B through contact 14 of relay ST in its right-hand position, front contact 18 of relay FIR, and either front contact 17 of relay RWP, or front contact 16 of relay NWP and back contact 17 of relay RWP, and then through front contact 15 of relay RPP and the winding of relay FIR to terminal C.

The two position device which is to be indicated at the office through the medium of my novel and improved arrangement utilizing the two code steps which indicate the three-position track switch, may as shown be a two-position relay CH corresponding to relay 2CH illustrated and described in Letters Patent of the United States No. 2,350,668, issued June 6, 1944, on an application filed by George W. Baughman and Norman F. Agnew. As explained in the Baughman et al. patent, the relay CH may function as a carrier change over relay controlled from the office for selecting one or the other of two carrier current units 1CCU and 2CCU conventionally represented at the station. It should be understood, however, that the same principle may be applied to indicate any two-position device, such as the power-off relay POR shown in the Quinlan application Serial No. 665,018, and is applicable whether polarized or neutral two-position relays are employed.

The previously mentioned switch indication relays NWP and RWP govern the transmission of switch indications from the station in the usual manner. That is to say, it is obvious from an inspection of the drawing that if an indication

code is transmitted from the station when relay NWP is picked up, wire 139 will be connected to terminal B at front contact 3 of relay NWP, and that when a code is transmitted with relay RWP picked up, wire 141 will be connected to terminal B at front contact 9 of relay RWP. In addition, the relays NWP and RWP cooperate with relays CH and FIR to connect terminal B to both wires 139 and 141 if an indication code is transmitted when relay CH is in its operated (or right-hand) position, relay FIR is released, and either relay NWP or RWP is picked up. If, for example, under the conditions assumed relay RWP is picked up to connect terminal B at its front contact 9 to wire 141, then terminal B at contact 19 of relay CH is connected to wire 139 over a circuit including contact 10 of relay CH in its right-hand position, back contact 11 of relay FIR, front contact 13 of relay RWP and back contact 8 of relay NWP. The relays CH and FIR therefore function under certain conditions to control the transmission of the fourth condition of the switch indication code, i. e. both steps having the one code character, which is utilized in a manner hereinafter pointed out to control at the office the indicating lamps 1CCK and 2CCK. The provision of this indication is of particular advantage in connection with remote control systems, since it may be utilized to convey information relative to the position of a carrier changeover relay in systems using duplicate carrier current units, or the position of a power-off relay, or other types of equipment employed in remote control systems and having two positions such as a normal position and an operated position. Thus in the case of the carrier changeover relay it enables the operator to have information provided as to which of the two duplicate sets of carrier equipment is in service, while in the case of the power-off relay information is furnished as to whether the equipment at the field station is operating from the normal source or being energized from the standby power source.

The condition of the apparatus shown in the drawing is that obtaining when switch W is locked in its normal position and relay CH is in its normal, or left-hand position as viewed in the drawing in which contact 19 of relay CH selects carrier unit 1CCU. In this condition of the apparatus relay NWP is picked up over contact 1 of switch mechanism SM and the relay holds its front contact 8 closed to prepare the circuit for connecting terminal B at the station to terminal 139 of one of the switch communication channels of the code. Relay ST also is energized in its stick circuit including its contact 2 closed in its energized, or left-hand position as shown in the drawing, the winding of relay ST, front contact 3 of relay NWP, back contact 4 of relay RWP, front contact 5 of relay FIR, front contact 6 of relay TR, contact 7 of relay CH in its normal or left-hand position, and the other terminal C of the energizing source of current. At the office, relay NWK is held energized over its stick circuit including front contact 21 of relay NWK and back contact 22 of relay D; and front contact 23 of relay NWK is held closed to complete an obvious energizing circuit for indication lamp NWE which reflects at the office the locked normal condition occupied by the track switch at the station. In addition, indication lamp 1CCK is energized over back contact 24 of relay CH to indicate at the office that carrier unit 1CCU at the station is selected for operation.

With relay CH in its normal or left-hand posi-

tion as illustrated in the drawing, the apparatus embodying my invention operates to control the indication lamps at the office, and particularly the switch indication lamps NWE and RWE, in accordance with indication codes transmitted from the station following a change in condition of the apparatus at the station, while maintaining the indication at the office reflecting the position of the carrier change-over relay CH at the station. For example, if a change occurs in the occupancy of track section T so that relay TR releases to reflect the presence of a train (or if relay TR subsequently picks up to indicate the train vacating the section), the shift in position of contact 6 of relay TR will momentarily open at that point the stick circuit of relay ST, and that relay will operate its contact 14 to its right-hand position to initiate an indication code. In this code terminal B at contact 8 of relay NWP is connected to terminal 139 so that terminal B at the office will be connected to terminal 49. When relay D at the office picks up to open its back contact 22 in the stick circuit of relay NWK, and contact 22 of relay D in its front position thereupon completes the pickup circuit for relay NWK extending from terminal 49 through back contact 25 of relay RWK, front contact 22 of relay D and the winding of relay NWK to terminal C. Relay NWK will therefore be held energized as long as relay D is held up, and when relay D releases its back contact 22 closes to re-establish the stick circuit of relay NWK so that the display of the switch indication lamp NWE is maintained. The starting relay ST will have been restored to its normally energized condition in the manner explained in the Jackel patent, after transmission of the station selecting portion of the indication code.

If, under the conditions assumed, the operator controls the switch mechanism SM to operate switch W to its reverse position, relay NWP will become deenergized as soon as mechanism SM unlocks the switch preparatory to operating it to the reverse position, and relay FIR will pick up over its circuit including back contacts 16 and 17 of relays NWP and RWP, respectively, so that relay FIR closes its front contact 18 to prepare its previously traced stick circuit. In addition, the starting relay ST will operate to its right-hand position to initiate an indication code in which both terminals 139 and 141 at the station will be deenergized due to the fact that both relays NWP and RWP are released. Under these conditions both terminals 49 and 51 at the office will be deenergized when relay D picks up, so that when back contact 22 of relay D opens, relay NWK becomes deenergized and releases to open its front contact 23 and deenergize lamp NWE, thereby to indicate that switch W at the station is in transit between its two extreme positions. Relay OIR at this time picks up over an obvious circuit including back contacts 26 and 27 of relays NWK and RWK and winding 28 of relay OIR; and relay OIR establishes a stick circuit including front contact 29 of relay D, front contact 30 of relay OIR and winding 28 of that relay. This stick circuit opens as soon as relay D releases, but relay OIR is held energized over its pickup circuit as long as both relays NWK and RWK remain released.

At the station, relay RWP picks up as soon as contact 1 is operated to its reverse position to indicate that switch W is operated to and locked in its reverse position, and back contact 4 of relay RWP opens to deenergize relay ST

so that its contact 14 operates to its right-hand position to complete the stick circuit of relay FIR through contact 14 of relay ST, front contact 18 of relay FIR, front contact 17 of relay RWP and front contact 15 of relay RPP. Contact 14 of relay ST also starts transmission of another indication code in which terminal B at contact 9 of relay RWP is connected to terminal 141 so that terminal B at the office is connected to terminal 51 when relay D picks up, and as a result relay RWK at the office picks up over a circuit which passes from terminal 51 through back contact 31 of relay NWK, front contact 32 of relay D and the winding of relay RWK. Relay RWK thereupon opens its back contact 27 in the circuit of winding 28 of relay OIR, but that relay remains energized over its stick circuit including its own front contact 30 and front contact 29 of relay D. Front contact 33 of relay RWK closes to energize lamp RWE to indicate that switch W at the station is locked in its reverse position, while front contact 34 of relay RWK also closes to prepare its stick circuit which is completed and holds relay RWK energized when relay D releases to close its back contact 32.

Relay FIR at the station became deenergized during the transmission of the indication code just described, when relay ST restored to normal to operate its contact 14 to its left-hand position at the end of the station selection portion of the indication code, but due to the slow releasing characteristics of relay FIR its armature was retained in its picked up position during the transmission of the remainder of the code. It should be noted that during this period back contact 11 of relay FIR will be held open, and that after the full indication code has been transmitted from the station and registered at the office, relay FIR will release at the end of its slow release interval to close its back contact 11, and to shift the position of its contact 5 in the circuit of relay ST, whereupon relay ST operates to initiate another indication code. In this code terminal B at the front contact of one of the switch indication relays (RWP) is connected to one of the wires 141, while with back contact 11 of relay FIR closed, and one switch indication relay (RWP) picked up and the other relay (NWP) released, a circuit is prepared for connecting terminal B at contact 10 of relay CH to the other wire 139. Under the conditions assumed, however, that is, with relay CH in its normal or left-hand position, terminal B is not connected to wire 139 during this code and as a result terminal B at the office will be connected only to wire 51, to hold up relay RWK when relay D picks up, and when relay D releases relay RWK remains held up over its stick circuit.

It is believed that the operation of the apparatus in response to the switch W being restored to its normal position with relay CH also in its normal position, will be readily apparent from the foregoing description taken in connection with an inspection of the drawing, it being understood of course that the apparatus will first function to transmit an "in-transit" indication during which relay FIR at the station is held energized and the two wires 139 and 141 at the station are both deenergized; that following the switch becoming locked in its normal position a "normal-position" code will be transmitted during which relay FIR is held up and wire 139 at the station is energized; and that after this code has been transmitted relay FIR will release to initiate another code in which wire 139 also is

energized, so that the indication apparatus at the office will be controlled to reflect the change of position of the switch at the station while maintaining the display of the carrier current indication without change.

The operations previously described are those normally obtaining in the system and are effected when line conditions are such that each of the various indication codes can be transmitted without loss of any code due to the inability to transmit because of the line being utilized for other code transmission. It sometimes happens, however, that when a change in condition of apparatus at a particular station occurs, the line is then in use under the control of a superior station, and in such event when the starting relay at the particular station is operated, it remains in its operated position until that station gains access to the line and can transmit its indications. In such cases it sometimes happens that when a switch at a station is controlled from one position to another, the starting relay at the station operates to condition the station to transmit a code, but the line cannot be obtained during the time that the switch is in transit and both the normal and reverse switch indication relays NWP and RWP are released to deenergize both of the switch indication channel wires 139 and 141 at that station, and that the line is made available only after the switch has completed its movement and is locked in its new position where the corresponding switch indication relay is picked up to apply energy to the station terminal of the corresponding switch indication channel of the code. In such event, therefore, the movement of the switch will of course be registered at the office, but the "in-transit" code which normally is provided will be omitted and the indication at the office will then change directly from one position of the switch to the other without the usual intervening "in-transit" indication. In conditions such as these where the "in-transit" switch indication is omitted, the apparatus embodying my invention operates to effect proper control over the switch indications and carrier indications, in a manner which I shall now explain in detail, it being assumed that with the switch W in its reverse position so that relay RWP at the station is picked up, and so that relay RWK and indication lamps RWE and CCK at the office are energized, the operator establishes a control over the station apparatus and causes switch W to restore to its normal position but line conditions prevent the transmission of a code from the station during the time the switch is unlocked and moving to its normal position. Thus, although relay RWP releases as soon as the switch is unlocked for movement, and relay RWP shifts its contact 4 in the circuit of relay ST so that relay ST operates to close its contact 14 in its operated or right-hand position to condition the apparatus for transmission of a code, the code is held off by line conditions until after the switch operates to and becomes locked in its normal position where relay NWP becomes energized and picks up. With the code held off, relay ST is retained in its operated position and relay FIR, which picked up when both relays NWP and RWP were released with the switch in transit, is held energized in its stick circuit completed when relay NWP closed its front contact 16, this stick circuit extending from terminal B through contact 14 of relay ST in its operated position, front contact 18 of relay FIR, front contact 16 of relay

NWP, back contact 17 of relay RWP, front contact 15 of relay RPP and the winding of relay FIR to terminal C.

This condition of the apparatus will obtain until such time as the equipment at the station can seize the communication line and transmit the indication code. At the end of the station selecting portion of this code, relay ST will restore and interrupt the stick circuit of relay FIR, but the latter relay will hold up due to its slow releasing characteristics until after the complete code has been transmitted and registered. In this code, terminal B at contact 8 of relay NWP will be connected to wire 139 with the result that terminal B at the office will be connected to wire 49 at a time when relay RWK is picked up, consequently relay OIR will pick up over a circuit which may be traced from terminal 49 through back contact 35 of relay NWK, front contact 36 of relay RWK and winding 37 of relay OIR to terminal C. Relay OIR thereupon closes its front contact 30 to prepare its stick circuit over front contact 29 of relay D when that relay picks up, and also closes its front contact 38 so that when relay D does pick up, relay CHK becomes energized by a circuit path connected in multiple with winding 37 of relay OIR and including front contact 38 of relay OIR, back contact 39 of relay CHK, front contact 40 of relay D and the winding of relay CHK. The energization of relay CHK is effected only momentarily, however, since when relay D picks up it opens at its back contact 32 the stick circuit of relay RWK, and with terminal 51 at the office deenergized, relay RWK is likewise deenergized and releases to open its front contact 36 in the circuits of relay OIR and CHK. Relay CHK is proportioned with slow pickup characteristics such that it will not pick up in the relatively short interval of time that it is energized under the conditions assumed. Inasmuch as back contact 25 of relay RWK is included in the pickup circuit of relay NWK, the latter relay remains released until relay RWK releases to close its back contact 25, whereupon relay NWK picks up because terminal B is connected to wire 49. The release of relay RWP results in deenergizing lamp RWE, while lamp NWE is lighted when relay NWK picks up. Then when relay D releases, relay NWK is held up over its stick circuit, and relay OIR releases.

After the complete indication code has been transmitted from the station and registered at the office, relay FIR will release at the station to shift the position of its contact 5 and cause relay ST to operate to initiate another indication code. This indication finds terminal B at front contact 8 of relay NWP connected to wire 139 so that terminal B at the office will be connected to wire 49. When relay D picks up, therefore, relay NWK will be held up and the apparatus at the office will hold relay NWK energized in its stick circuit after relay D releases.

Under the conditions just described, it is apparent that the apparatus functions to change the indications displayed by the switch indication lamps, while maintaining without change the display of the carrier unit indication, in the case where the switch position is changed and no "in-transit" indication is provided to the office. It is, of course, obvious that the apparatus will function in a correspondingly similar manner to register the change of switch position from normal to reverse, while maintaining the display of the carrier unit indication, in the event that the "in-

"transit" indication is missed when the switch is moving from its normal to its reverse position.

If now, with switch W in its normal position and this condition registered at the office by the energization of relay NWK and lamp NWE, the operator reverses the position of relay CH so that contact 19 in its right-hand position selects carrier unit 2CCU, the shift of position of contact 7 will cause relay ST to operate and its contact 14 to close in its right-hand position to initiate transmission of an indication code. In this case, terminal B at contact 8 of relay NWP is connected to wire 139, while terminal B is connected to wire 141 over the circuit completed through contact 10 of relay CH in its right-hand position, back contact 11 of relay FIR, front contact 12 of relay NWP and back contact 9 of relay RWP. It should be noted that if switch W had been in its reverse position when relay CH was reversed, then with relay RWP picked up to connect terminal B at front contact 9 to wire 141, the other wire 139 would also be energized over back contact 8 of relay NWP, front contact 13 of relay RWP, back contact 11 of relay FIR and contact 10 of relay CH in its reverse or right-hand position. It follows that when a code is initiated from the station by reversing relay CH, both terminals 139 and 141 will be energized, one being connected to terminal B at a front contact of the switch indication relay that is energized and repeats the position of the switch, and the other being connected to terminal B at contact 10 of relay CH.

At the office, both terminals 49 and 51 will be energized so that before relay D picks up, relay OIR picks up over its circuit from terminal 51 through back contact 41 of relay RWK, front contact 42 of relay NWK and winding 37 of relay OIR. Relay OIR closes its front contact 30 to prepare its stick circuit and its front contact 38 to prepare the circuit for relay CHK that is completed, in multiple with winding 37 of relay OIR, when relay D picks up to complete a path including front contact 38 of relay OIR, back contact 39 of relay CHK, front contact 40 of relay D and the winding of relay CHK. Relay CHK thereupon picks up and operates its make-before-break contact 39 from its back to its front position, in which another circuit is completed for relay CHK, extending from terminal 49 through front contact 35 of relay NWK, front contact 43 of relay OIR, front contact 39 of relay CHK, front contact 40 of relay D and the winding of relay CHK. Relay CHK of course operates its contact 24 away from its back point to deenergize lamp 1CCK, and contact 24 closes to its front point to energize lamp 2CCK, thereby to indicate the selection of unit 2CCU at the station.

When relay D picked up, relay NWK was held energized with energy applied to terminal 49, and relay NWK held open its back contact 31 in the circuit of relay RWK so as to maintain that relay released despite the application of energy to its terminal 51. Then when relay D releases, relay NWK is held energized over its stick circuit, while relay CHK is likewise held energized in its stick circuit including its own front contact 44 and back contact 40 of relay D. The indication lamps NWE and 2CCK therefore are maintained energized to indicate that switch W is normal and relay CH is reversed.

The apparatus at the office is arranged to maintain relay CHK energized without change by indication codes received from the station until a code is received which includes steps indicating that relay CH has been restored to its normal

position. For example, if with relay CH in its reverse position the operator controls switch mechanism SM to operate switch W to its reverse position, relay NWP will release as soon as the switch unlocks, and relay NWP will close its back contact 16 to pick up relay FIR, and will shift its contact 3 to cause relay ST to operate and initiate a code. During this code back contact 11 of relay FIR will be held open, and both wires 139 and 141 will be deenergized, so that at the office relay NWK will release when relay D picks up. The release of relay NWK deenergizes lamp NWE to signify that switch W is in transit between extreme positions, and also results in closing back contact 26 of relay NWK to complete a circuit for relay OIR, which circuit includes back contacts 26 and 27 of relays NWK and RWK, respectively, and winding 28 of relay OIR, so that relay OIR picks up. Relay NWK also closes its back contact 45 when it releases, to complete a circuit including that contact, back contact 46 of relay RWK, front contact 39 of relay CHK, front contact 40 of relay D and the winding of relay CHK, so that even though the stick circuit of relay CHK is opened when relay D picks up, relay CHK is held energized during the time that relay D is held up, over a circuit completed when both relays NWK and RWK are released. Relay CHK is of course held energized in its stick circuit when relay D releases, and relay CHK maintains the display of lamp 2CCK.

When switch W at the station is locked in its reverse position, relay RWP picks up to shift the position of its contact 4 and therefore operate relay ST to start an indication code. Contact 14 of relay ST in its reverse position also completes the stick circuit for relay FIR, through its own front contact 18 and front contact 17 of relay RWP, and relay FIR accordingly is held energized during this code until relay ST restores at the end of the station selecting portion of the code, with the relay FIR being held up for the remainder of the code by its slow releasing features. During this code, therefore, contact 11 of relay FIR is held open to isolate terminal B at contact 10 of relay CH from the wires 139 and 141, and in this code the wire 141 is energized by terminal B at front contact 9 of relay RWP. This results in the energization of terminal 51 at the office, and when relay D picks up, relay RWK also picks up to close its front contact 33 and energize lamp RWE to signify that switch W is in its reverse position. Relay OIR, which was held energized over back contacts of relays NWK and RWK until relay RWK picked up, is now held energized in its stick circuit completed over front contact 29 of relay D, and relay CHK is now held energized over front contact 41 of relay RWK, front contact 43 of relay OIR, front contact 39 of relay CHK, front contact 40 of relay D and the winding of relay CHK. When relay D releases, relay RWK is held energized over its stick circuit including back contact 32 of relay D; relay CHK also is held energized in its stick circuit completed over back contact 40 of relay D; while relay OIR releases. It follows, therefore, that relay RWK at the office is picked up to establish the reverse switch indication at the office, while the display of the reverse carrier current indication is maintained.

At the end of the slow release period of relay FIR, its back contact 11 closes and contact 5 is operated to cause relay ST to reverse and initiate another code. In this code both wires 139 and 141 are energized, wire 141 over front contact 9

of relay RWP, and wire 139 over back contact 8 of relay NWP, front contact 13 of relay RWP, back contact 11 of relay FIR and reverse contact 10 of relay CH. At the office, therefore, both wires 49 and 51 are energized so that with relay RWK picked up, relay OIR picks up over the circuit from terminal 49 through back contact 35 of relay NWK, front contact 36 of relay RWK and winding 37 of relay OIR. When relay D subsequently picks up to open the stick circuits of relays RWK and CHK, relay RWK is held energized over its pickup circuit including back contact 31 of relay NWK and front contact 32 of relay D; relay CHK is held energized over its circuit including front contact 40 of relay D, front contact 39 of relay CHK, front contact 43 of relay OIR, front contact 41 of relay RWK and terminal 51; while relay OIR is held energized over its stick circuit including front contact 29 of relay D. At the release of relay D, relay OIR also releases but relays RWK and CHK remain picked up in their stick circuits.

If the operator should reverse relay CH under the conditions assumed, contact 19 of relay CH will of course operate to its normal position to select unit 1CCU, and the shift of contact 1 results in operation of relay ST to initiate a code, in which terminal B at front contact 9 of relay RWP is connected to wire 141. When relay D picks up at the office, to open the stick circuits for relays RWK and CHK, relay RWK will be held energized in its pickup circuit since terminal B is connected at this time to wire 51, but relay CHK will release to open its front contact 24 to deenergize lamp 2CCK. The other lamp 1CCK will, however, be energized over contact 24 of relay CHK in its back position, to indicate that relay CH is in its normal position at the station where it selects carrier unit 1CCU. At the release of relay D, relay RWK will be held energized in its stick circuit while relay CHK will remain released, and consequently the apparatus will function to maintain the display of the switch indication at the office while altering the display of the carrier unit indication to accord with a change in selection of units at the station.

The system arrangement involving contact 5 of relay FIR in the stick circuit of starting relay ST which assures the transmission from the station of two indication codes each time switch W reaches and is locked in its extreme position following a change of position of the switch, is of particular advantage in the case where the operator effects a change in the positions of both switch W and of changeover relay CH. That is to say, if with the switch W and relay CH both reversed and relays RWK and CHK held energized at the office to indicate this condition, a control from the office causes switch W and relay CH to operate to their respective normal positions, the first indication transmitted following the shift in position of relays RWP and CH finds both terminals 139 and 141 deenergized, and as a result relay RWK will be released to cause the "in-transit" indication to be exhibited at this time. Relay OIR will be picked up with both relays NWK and RWK released to close their back contacts 26 and 27 respectively, and relay CHK will be held energized over its circuit including its front contact 39 and back contacts 45 and 46 of relays NWK and RWK, respectively. Then when switch W reaches and is locked in its normal position, relay NWP shifts its position to operate relay ST and the latter initiates another code, and also holds relay FIR

(which picked up when both relays NWP and RWP were released) energized in its stick circuit. The code initiated by relay NWP picking up finds terminal B at front contact 8 of relay NWP connected to terminal 139 and as a result relay NWK at the office picks up and closes its front contact 23 to energize lamp NWE, and front contact 35 to hold relay CHK energized. Relays NWK and CHK remain energized in their respective stick circuits when relay D at the office releases. After the transmission of this first code, relay FIR will release to operate relay ST and initiate the second code. This also finds terminal B at front contact 8 of relay NWP connected to terminal 139 and as a result relay NWK is held energized when relay D picks up at the office. Relay OIR is now deenergized so that when the stick circuit of relay CHK is broken by relay D picking up, relay CHK is deenergized and releases to cause lamp 1CCK to become lighted, and lamp 2CCK to be extinguished. Then when relay D releases, relay NWK is held up and the office indicates that switch W and relay CH are in their respective normal positions.

It should be noted that relay CHK is controlled by the second indication transmitted in this case, and that only where the second indication is the same as the first will relay CHK be released if it is energized at the office. The transmission of two indications one reflecting the position of the track switch and the other reflecting the position of relay CH is advantageous following each movement of the switch into an extreme position in order to afford information relating to both the switch and changeover relay. This arrangement is therefore to be preferred over that shown in Fig. 1a and hereinafter described, in which the second indication is provided only if relay CH is reversed.

The system arrangement also provides for energizing relay FIR whenever the station disconnect relay RPP is released and closes its back contact 15. As pointed out in Jackel Patent 2,411,375, when relay RPP is released the station cannot communicate with the office but the office can communicate with the station. If during the period that relay RPP is released, the position of switch W has been changed, then relay ST will be in its operated position where it remains until relay RPP is picked up and an indication code is transmitted to the office. When relay RPP picks up, its front contact 15 closes to complete the stick circuit of relay FIR closed through contact 14 of relay ST in its operated position, consequently the first code transmitted after relay RPP picks up will reflect the position of switch W, and after that code has been received and registered at the office, relay FIR will release to initiate the second code in which the position of relay CH will be reflected. Controlling relay FIR by relay RPP in this manner therefore permits review of both switch W and relay CH after the station equipment is restored to service by picking up relay RPP.

From the foregoing it is readily apparent that I have provided a system in which a two-position device at a station can be indicated at an office over the two steps used to indicate the position of a three-position device at the station. The system is arranged to employ an intermediate relay FIR at the station and an intermediate relay OIR at the office. The field station intermediate relay is energized whenever the three-position device occupies its intermediate position and is retained in its picked up position until

after the station transmits the code indicating that the device has reached and occupies its extreme position. If the field station intermediate relay is released when a code is transmitted from the station, it conditions the code under certain conditions to include steps corresponding to the energization of both terminals of the switch steps and consequently provides a fourth indication by use of these two steps, the determination of whether the fourth indication is or is not transmitted when relay FIR is released, being made by the position of the two-position device with which the fourth indication is associated.

The office station intermediate relay OIR is energized whenever both switch indication relays at the office are released, or whenever with either switch indication relay picked up a code is received which results in the energization of the channel for the other (i. e. the released) indication relay. The office intermediate relay functions to control an additional relay provided at the office to indicate the two-position device at the station, with the intermediate relay at the office controlling the additional indication relay so as to effect its energization when the fourth indication, e. g. both switch steps energized, is received at the office, and arranged to maintain the energization of the additional indication relay until with relay FIR released at the station, a code is received which contains only one energized switch step. It follows that by use of the intermediate relays FIR and OIR at the station and office respectively, in addition to the necessary indication and repeating relays provided at both the office and station, a system is provided which indicates over the two switch steps of a code, not only the three-position switch, but also a two-position device, with the indications of either of the two devices being maintained without change upon receipt of codes indicating a change in position of the other of such devices.

In the system heretofore described, the field station intermediate relay FIR is represented with its contact 5 interposed directly in the stick circuit of relay ST, so that whenever the position of switch W shifts from either extreme position to the other, two indication codes are transmitted to the station after the switch reaches and is locked in its other extreme position. Of these, the first indicates the locked position of the switch and the second is initiated when relay FIR releases so that in this second code only one, or both, of the switch indication channels at the station will be energized dependent upon whether the two-position device is in its normal or reverse position, respectively. A slight modification of the system of Fig. 1 is represented in Fig. 1a which shows the stick circuit of relay ST arranged to include contact 5 of relay FIR only when relay CH is in its operated position where its contact 7 will be in its right-hand position to interpose contact 5 of relay FIR in the circuit of relay CH. It follows that if the circuit of Fig. 1a were substituted for the circuit of relay ST shown in Fig. 1, then although relay FIR would be picked up and released during the operation of the apparatus at the station in exactly the same manner as has been pointed out hereinbefore, the relay FIR would not control the operation of relay ST unless relay CH is in its operated position, and therefore after the operation of the switch from one extreme position to the other, one indication code will be transmitted to the office if relay CH is in its normal position, with two indication codes being transmitted only

in the case where relay CH is in its operated position. The alternative arrangement shown in Fig. 1a therefore has the advantage of requiring the transmission of the second successive code from the station only when relay CH is positioned to provide the second code with steps conveying the fourth indication, e. g. both switch steps long.

Although I have herein shown and described only two forms of remote control apparatus embodying my invention, it is understood that various changes and modifications may be made therein within the scope of the appended claims without departing from the spirit and scope of my invention.

Having thus described my invention, what I claim is:

1. In a centralized traffic control system of the type described for railroads, the combination with an office and a station and a communication system linking said office and station, said station provided with a first device having two extreme positions and an intermediate position and with a second device having a normal and an operated position, said communication system provided with two channels over which code elements having one character or another may be transmitted and including a station starting relay having a normal and an operated position in the latter of which it initiates transmission of code elements over said channels, said system including means controlled by said first device in response to a movement into or out of either extreme position and by said second device in response to a shift in its position for causing operation of said starting relay to initiate the transmission of code elements over said channels, means governed by said first device for controlling said communication system so that one or the other or both of the code elements transmitted over said channels have said one character depending upon whether said first device is in one or the other of its extreme positions or is in its intermediate position, of means governed by said second device for controlling said communication system so that the code elements transmitted over said channels both have said other character when said second device is in its operated position, and means governed by said first device rendered effective whenever said first device occupies its intermediate position for establishing the transmission of two sets of code elements when said first device subsequently moves into an extreme position, with character of the first set of code elements controlled by said first device and that of said second set controlled by said second device.

2. In a centralized traffic control system for railroads, the combination with an office and a station and a communication system linking said office and station, said station provided with a first device having two extreme positions and an intermediate position and with a second device having a normal and an operated position, said communication system provided with two channels over which code elements having one character or another may be transmitted and including a station starting relay having a normal and an operated position in the latter of which it initiates transmission of code elements over said channels, means governed by said first device for controlling said communication system so that one or the other or both of the code elements transmitted over said channels have said one character depending upon whether said first device is in one or the other of its extreme positions

or is in its intermediate position, means governed by said second device for controlling said communication system so that both said code elements have said other character if said second device is in its said operated position, of another relay, means governed by said first device and by said second device and by said other relay in response to a shift of position of said first or second device or said other relay for causing said starting relay to operate and initiate the transmission of code over said channels, means governed by said starting relay and by said first device for controlling said other relay so that whenever said first device moves from its intermediate position into either extreme position the transmission of the code elements initiated thereby is followed by a shift in position of said other relay, whereby said system is caused to transmit two successive groups of code elements over said channels whenever said first device moves into either extreme position, and means governed by said other relay for controlling said communication system so that the character of the code elements transmitted in the first group is controlled by said first device and that of the second group is controlled by said second device.

3. In a centralized traffic control system of the type described for railroads, the combination with an office and a station and a communication system linking said office and station, said station provided with a first device having two extreme positions and an intermediate position and with a second device having a normal and an operated position, said communication system provided with two channels over which code elements having one character or another may be transmitted, said communication system provided with a station starting relay having a normal and an operated position in the latter of which it initiates transmission of code elements over said channels, means governed by said first device for controlling said communication system so that one or the other or both of the code elements transmitted over said channels have said one character depending upon whether said first device is in one or the other of its two extreme positions or is in its intermediate position, of another relay, means governed by said first device and by said other relay in response to a shift of position of that first device or other relay for causing said starting relay to operate and initiate the transmission of code over said channels, means governed by said starting relay and by said first device for controlling said other relay so that if said second device is in its operated position whenever said first device moves into either extreme position the transmission of the code elements initiated thereby is followed by a shift in position of said other relay, whereby said system is caused to transmit two successive groups of code elements over said channels whenever said first device moves into either extreme position, and means governed by said other relay for controlling said communication system so that the code elements transmitted in the second group both have said other character, the character of the code elements in the first group being controlled by said first device.

4. In a remote control system, the combination with an office and a station and a communication system linking said office and station, said station provided with a first device having two extreme positions and an intermediate position and with a second device having a normal and an operated position, said communication system

provided with two channels over which code elements having one character or another may be transmitted and including a station starting relay having a normal and an operated position in the latter of which it initiates transmission of code elements over said channels, said system including means controlled by said first device in response to a movement into or out of either extreme position and by said second device in response to any shift of position for causing operation of said starting relay to initiate the transmission of code elements over said channels, means governed by said first device for controlling said communication system so that the code element transmitted over one of said channels has said one character or the other depending upon whether or not said first device is in one of its extreme positions and the code element transmitted over the other of said channels has said one character or the other depending upon whether or not said first device is in the other of its extreme positions and both said code elements have said other character if said first device is in its said intermediate position, of another relay, means governed by said other relay in response to a shift of position of that relay for causing said starting relay to operate and initiate the transmission of code over said channels, means governed by said starting relay and by said first device for controlling said other relay so that whenever said first device moves into either extreme position the transmission of the code elements initiated thereby is followed by a shift in position of said other relay, whereby said system is caused to transmit two successive groups of code elements over said channels whenever said first device moves into either extreme position, and means governed by said second device for controlling said communication system so that the code elements caused to be transmitted in response to a shift of position of said other relay both have said one character if said second device is in its said operated position.

5. In a remote control system, the combination with an office and a station and a communication system linking said office and station, said station provided with a first device having two extreme positions and an intermediate position and with a second device having a normal and an operated position, said communication system provided with two channels over which code elements having one character or another may be transmitted and including a station starting relay having a normal and an operated position in the latter of which it initiates transmission of code elements over said channels, said system including means controlled by said first device in response to a movement into or out of either extreme position and by said second device in response to any shift in its position for causing operation of said starting relay to initiate the transmission of code elements over said channels, said system also including means for controlling said communication system by said first device so that the code element transmitted over one of said channels has said one character or the other depending upon whether or not said first device is in one of its extreme positions and the code element transmitted over the other of said channels has said one character or the other depending upon whether or not said first device is in the other of its extreme positions and both said code elements have said other character if said first device is in its said intermediate position, of another relay, means governed by said other relay in response to a shift in its position for causing operation of said starting relay to initiate the transmission of code elements over said channels, said system also having means governed by said

second device provided that device occupies its said operated position for controlling said communication system so that both code elements transmitted have said one character, of another relay, means governed by said other relay in response to a shift of position of that relay for causing said starting relay to operate and initiate the transmission of code over said channels, means governed by said starting relay and by said first device for controlling said other relay so that whenever said first device moves into either extreme position the transmission of the code elements initiated thereby is followed by a shift in position of said other relay, whereby said system is caused to transmit two successive groups of code elements over said channels whenever said first device moves into either extreme position, the character of the code elements of the first group governed by said first device and the character of the code elements of the second group governed by said second device if it is then in its operated position.

6. In a remote control system, the combination with an office and a station and a communication system linking said office and station, said station provided with a first device having two extreme positions and an intermediate position and with a second device having a normal and an operated position, said communication system provided with two channels over which code elements having one character or another may be transmitted and including a station starting relay having a normal and an operated position in the latter of which it initiates transmission of code elements over said channels, said system including means controlled by said first device in response to a movement into or out of either extreme position and by said second device in response to any shift in its position for causing operation of said starting relay to initiate the transmission of code elements over said channels, said system also including means for controlling said communication system by said first device so that the code element transmitted over one of said channels has said one character or the other depending upon whether or not said first device is in one of its extreme positions and the code element transmitted over the other of said channels has said one character or the other depending upon whether or not said first device is in the other of its extreme positions and both said code elements have said other character if said first device is in its said intermediate position, said system also having means governed by said second device provided that device occupies its said operated position for controlling said communication system so that both code elements transmitted have said one character, of another relay, means governed by said starting relay and by said first device for controlling said other relay so that whenever said first device moves into either extreme position the transmission of the code elements initiated thereby is followed by a shift in position of said other relay, means governed by said other relay in response to a shift of position of that relay provided said second device is in its operated position for causing said starting relay to operate and initiate the transmission of code over said channels, whereby said system is caused to transmit two successive groups of code elements over said channels whenever said first device moves into either extreme position when said second device is in its operated position, the character of the code elements of the first group governed by said

first device and the character of the code elements of the second group governed by said second device.

7. In a remote control system, the combination with an office and a station and a communication system linking said office and station, said station provided with a plurality of elements including a device having two extreme positions and an intermediate position, and said communication system provided with two channels over which code elements having one character or another may be transmitted and including a station starting relay having a normal and an operated position in the latter of which it initiates transmission of code elements over said channels, of another relay, a pickup circuit for said other relay completed when said device is in its intermediate position, a stick circuit for said other relay completed over a front contact of that relay when said starting relay is in its operated position and said device is in either of its extreme positions, means for controlling said starting relay to cause it to operate to its said operated position upon a change in position of any of said plurality of elements or said other relay, means for controlling said communication system by said device so that the code element transmitted over said one channel has said one character or the other depending upon whether or not said device is in one of its extreme positions and the code element transmitted over the other channel has said one character or the other depending upon whether or not said device is in the other of its extreme positions, and means effective at times if said other relay is released for controlling said communication system so that the code elements transmitted over both said channels have said one character.

8. In a remote control system, the combination with an office and a station and a communication system linking said office and station, said station provided with a device having two extreme positions and an intermediate position, and said communication system provided with two channels over which code elements having one character or another may be transmitted and including a station starting relay having a normal and an operated position in the latter of which it initiates transmission of code elements over said channels, of another relay, a pickup circuit for said other relay completed when said device is in its intermediate position, a stick circuit for said other relay completed over a front contact of that relay when said starting relay is in its operated position and said device is in either of its extreme positions, means for controlling said starting relay to cause it to operate to its said operated position upon a change in position of said device or said other relay, means for controlling said communication system by said device so that the code element transmitted over said one channel has said one character or the other depending upon whether or not said device is in one of its extreme positions and the code element transmitted over the other channel has said one character or the other depending upon whether or not said device is in the other of its extreme positions, means effective at times if said other relay is released for controlling said communication system so that the code elements transmitted over both said channels have said one character.

9. In a remote control system, the combination with an office and a station and a communication system linking said office and station, said station provided with a device having two extreme positions and an intermediate position, and said communication system provided with two channels over which code elements having one character or another may be transmitted and including a station starting relay having a normal and an operated position in the latter of which it initiates transmission of code elements over said channels, of another relay, a pickup circuit for said other relay completed when said device is in its intermediate position, a stick circuit for said other relay completed over a front contact of that relay when said starting relay is in its operated position and said device is in either of its extreme positions, means for controlling said starting relay to cause it to operate to its said operated position upon a change in position of said device or said other relay, means for controlling said communication system by said device so that the code element transmitted over said one channel has said one character or the other depending upon whether or not said device is in one of its extreme positions and the code element transmitted over the other channel has said one character or the other depending upon whether or not said device is in the other of its extreme positions, means effective at times if said other relay is released for controlling said communication system so that the code elements transmitted over both said channels have said one character, and means at said office selectively responsive to the character of the code elements transmitted over said two channels.

21

9. In a remote control system, the combination with an office and a station and a communication system linking said office and station, said station provided with a first device having two extreme positions and an intermediate position and with a second device having a normal and an operated position, and said communication system provided with two channels over which code elements having one character or another may be transmitted and including a station starting relay having a normal and an operated position in the latter of which it initiates transmission of code elements over said channels, of another relay, a pickup circuit for said other relay completed when said first device is in its intermediate position, a stick circuit for said other relay completed over a front contact of that relay when said starting relay is in its operated position and said first device is in either of its extreme positions, means for controlling said starting relay to cause it to operate to its said operated position upon a change in position of said first or second device or said other relay, means for controlling said communication system by said first device so that the code element transmitted over said one channel has said one character or the other depending upon whether or not said first device is in one of its extreme positions and the code element transmitted over the other channel has said one character or the other depending upon whether or not said first device is in the other of its extreme positions, and means governed by said second device in its operated position effective if said other relay is released for controlling said communication system so that the code elements transmitted over both said channels have said one character.

10. In a remote control system, the combination with an office and a station and a communication system linking said office and station, said station provided with a first device having two extreme positions and an intermediate position and with a second device having a normal and an operated position, and said communication system provided with two channels over which code elements having one character or another may be transmitted and including a station starting relay having a normal and an operated position in the latter of which it initiates transmission of code elements over said channels, of an intermediate relay, a station disconnect relay, a pickup circuit for said intermediate relay completed when said station disconnect relay is released, a second pickup circuit for said intermediate relay completed over a front contact of said station disconnect relay whenever said first device is in its intermediate position, a stick circuit for said intermediate relay completed over a front contact of that relay and a front contact of said station disconnect relay when said starting relay is in its operated position and said first device is in either of its extreme positions, means for controlling said starting relay to cause it to operate to its said operated position upon a change in position of said first or second device or said intermediate relay, means for controlling said communication system by said first device so that the code element transmitted over said one channel has said one character or the other depending upon whether or not said first device is in one of its extreme positions and the code element transmitted over the other channel has said one character or the other depending upon whether or not said first device is in the other of its extreme positions, and means governed by

22

said second device in its operated position effective if said intermediate relay is released for controlling said communication system so that the code elements transmitted over both said channels have said one character.

11. In a remote control system, the combination with an office and a station and a communication system linking said office and station and provided with two channels over which code elements having one character or another may be transmitted, said station provided with means for controlling the character of the code elements transmitted over said channels, of two indication relays at said office one for each channel, a pickup circuit for each indication relay supplied with energy only when a code element of said one character is transmitted over the associated channel and including a back contact of the other indication relay, a stick circuit effective if an indication relay is picked up by a code element of said one character transmitted over its associated channel to maintain that relay picked up until code elements are subsequently transmitted over said channels, indication means at said office selectively controlled by said two indication relays, another relay at said office, a first circuit for picking up said other relay completed when both said indication relays are released, a second circuit for picking up said other relay completed when a code element of said one character is transmitted over one of said channels and the indication relay associated with the other of said channels is picked up, and additional indication means at said office selectively controlled by said two indication relays and by said other relay.

12. In a remote control system, the combination with an office and a station and a communication system linking said office and station and provided with two channels over which code elements having one character or another may be transmitted, said station provided with means for controlling the character of the code elements transmitted over said channels, of two indication relays at said office one for each channel, a pickup circuit for each indication relay supplied with energy only when a code element of said one character is transmitted over the associated channel and including a back contact of the other indication relay, a stick circuit effective if an indication relay is picked up by a code element of said one character transmitted over its associated channel to maintain that relay picked up until code elements are subsequently transmitted over said channels, another relay at said office, a first circuit for picking up said other relay completed when both said indication relays are released, a second circuit for picking up said other relay completed if a code element of said one character is transmitted over one of said channels when the indication relay associated with the other of said channels is picked up, a third indication relay at said office, a branch path in said second circuit including a front contact of said other relay for picking up said third indication relay, and a stick circuit effective if said third indication relay is picked up over said branch path to hold that relay picked up until code elements subsequently are received at said office.

13. In a centralized traffic controlling system for railroads, the combination with an office and a station and a communication system linking said office and station and provided with two channels over which code elements having one character or another may be transmitted, said station provided with means for controlling the

character of the code elements transmitted over said channels, of two indication relays at said office one for each channel, a pickup circuit for each indication relay supplied with energy only when a code element of said one character is transmitted over the associated channel and including a back contact of the other indication relay, a stick circuit effective if an indication relay is picked up by a code element of said one character transmitted over its associated channel to maintain that relay picked up until code elements are subsequently transmitted over said channels, another relay at said office, a first circuit for picking up said other relay completed when both said indication relays are released, a second circuit for picking up said other relay completed when a code element of said one character is transmitted over one of said channels and the indication relay associated with the other of said channels is picked up, a third indication relay at said office, a branch path in said second circuit including a front contact of said other relay for picking up said third indication relay, stick circuit means effective if said third indication relay is picked up over said branch path to hold that relay picked up until code elements subsequently are received at said office, additional stick circuit means for said third indication relay effective during receipt of code elements if a code element of said one character is received when the associated indication relay and said other relay are picked up, and another stick circuit means for said third indication relay effective when both indication relays are released.

14. In a centralized traffic controlling system for railroads, the combination with an office and a station and a communication system linking said office and station and provided with two channels over which code elements having one character or another may be transmitted, said station provided with means for controlling the character of the code elements transmitted over said channels, of two indication relays at said office one for each channel, a pickup circuit for each indication relay supplied with energy only when a code element of said one character is transmitted over the associated channel and including a back contact of the other indication relay, a stick circuit effective if an indication relay is picked up by a code element of said one character transmitted over its associated channel to maintain that relay picked up until code elements are subsequently transmitted over said channels, another relay at said office, a first circuit for picking up said other relay completed when both said indication relays are released, a second circuit for picking up said other relay completed when a code element of said one character is transmitted over one of said channels and the indication relay associated with the other of said channels is picked up, a third indication relay at said office, a branch path in said second circuit completed when said other relay picks up for picking up said third indication relay, stick circuit means effective if said third indication relay is picked up over said branch path to hold that relay picked up until code elements subsequently are received at said office, additional stick circuit means for said third indication relay effective during receipt of code elements if a code element of said one character is received when the associated indication relay and said other relay are picked up, another stick circuit means for said third indication relay effective when both indication relays are released, and indication means selectively controlled by

said two indication relays and other indication means controlled by said third indication relay.

15. In a centralized traffic control system of the type described for railroads, the combination with an office and a station and a communication system linking said office and station, said station provided with a first device having two extreme positions and an intermediate position and with a second device having a normal and an operated position, said communication system provided with two channels over said code elements having one character or another may be transmitted and including a station starting relay having a normal and an operated position in the latter of which it initiates transmission of code elements over said channels, said system including means controlled by said first device in response to a movement into or out of either extreme position and by said second device in response to a shift in its position for causing operation of said starting relay to initiate the transmission of code elements over said channels, means governed by said first device for controlling said communication system so that one or the other or both of the code elements transmitted over said channels have said one character depending upon whether said first device is in one or the other of its extreme positions or is in its intermediate position, of means governed by said second device for controlling said communication system so that the code elements transmitted over said channels both have said other character when said second device is in its operated position, means governed by said first device rendered effective whenever said first device occupies its intermediate position for establishing the transmission of two sets of code elements when said first device subsequently moves into an extreme position, with the character of the first set of code elements controlled by said first device and that of said second set controlled by said second device, two indication relays at said office one for each channel, a pickup circuit for each indication relay supplied with energy only when a code element of said one character is transmitted over the associated channel and including a back contact of the other indication relay, a stick circuit effective if an indication relay is picked up by a code element of said one character transmitted over its associated channel to maintain that relay picked up until code elements are subsequently transmitted over said channels, another relay at said office, a first circuit for picking up said other relay completed when a code element of said one character is transmitted over one of said channels and the indication relay associated with the other of said channels is picked up, a third indication relay at said office, a branch path in said second circuit including a front contact of said other relay for picking up said third indication relay, stick circuit means effective if said third indication relay is picked up over said branch path to hold that relay picked up until code elements subsequently are received at said office, additional stick circuit means for said third indication relay effective during receipt of code elements if a code element of said one character is received when the associated indication relay and said other relay are picked up, and another stick circuit means for said third indication relay effective when both indication relays are released.

16. In a centralized traffic control system of

the type described for railroads, the combination with an office and a station and a communication system linking said office and station, said station provided with a first device having two extreme positions and an intermediate position and with a second device having a normal and an operated position, said communication system provided with two channels over which code elements having one character or another may be transmitted and including a station starting relay having a normal and an operated position in the latter of which it initiates transmission of code elements over said channels, said system including means controlled by said first device in response to a movement into or out of either extreme position and by said second device in response to a shift in its position for causing operation of said starting relay to initiate the transmission of code elements over said channels, means governed by said first device for controlling said communication system so that one or the other or both of the code elements transmitted over said channels have said one character depending upon whether said first device is in one or the other of its extreme positions or is in its intermediate position, of means governed by said second device for controlling said communication system so that the code elements transmitted over said channels both have said other character when said second device is in its operated position, means governed by said first device rendered effective whenever said first device occupies its intermediate position for establishing the transmission of two sets of code elements when said first device subsequently moves into an extreme position, with the character of the first set of code elements controlled by said first device and that of said second set controlled by said second device, two indication relays at said office one for each channel, a 40 pickup circuit for each indication relay supplied

with energy only when a code element of said one character is transmitted over the associated channel and including a back contact of the other indication relay, a stick circuit effective if an indication relay is picked up by a code element of said one character transmitted over its associated channel to maintain that relay picked up until code elements are subsequently transmitted over said channels, means controlled by said two indication relays for indicating at said office the position occupied at said station by said first device, another relay at said office, a first circuit for picking up said other relay completed when both said indication relays are released, a second circuit for picking up said other relay completed when a code element of said one character is transmitted over one of said channels and the indication relay associated with the other of said channels is picked up, a third indication relay at said office, a branch path in said second circuit including a front contact of said other relay for picking up said third indication relay, stick circuit means effective if said third indication relay is picked up over said branch path to hold that relay picked up until code elements subsequently are received at said office, additional stick circuit means for said third indication relay effective during receipt of code elements if said other relay is picked up and a code element of said one character is received when the associated indication relay is picked up, another stick circuit means for said third indication relay effective when both indication relays are released, and means controlled by said third indication relay for indicating at said office the position occupied at said station by said second device.
